UNITED STATES PATENT OFFICE

132,821

DESIGN FOR A SLANT ROOF LOUVER

Freeland H. Leslie, Chicago, Ill.

Application March 30, 1942, Serial No. 106,385

Term of patent 14 years

To all whom it may concern:

Be it known that I, Freeland H. Leslie, a citizen of the United States, residing at Chicago, in the county of Cook and State of Illinois, have invented a new, original, and ornamental Design for a Slant Roof Louver, of which the following is a specification, reference being had to the accompanying drawing, forming part thereof.

Figure 1 is a top perspective view of a slant roof louver showing my new design;

Figure 2 is a side elevational view thereof; and
Figure 3 is a front elevational view thereof.

I claim:

The ornamental design for a slant roof louver, substantially as shown.

FREELAND H. LESLIE.
